[57] CLAIM

The ornamental design for a protective and warming bonnet for food, as shown and described.

DESCRIPTION

FIG. 1 is a perspective view of a protective and warming bonnet for food, showing our new design;

FIG. 2 is a side perspective view of the protective and warming bonnet for food shown in FIG. 1;

FIG. 3 is a perspective view, with the bonnet partially open, of the protective and warming bonnet for food shown in FIG. 1;

FIG. 4 is a perspective view with the bonnet almost entirely open, of the protective and warming bonnet for food as shown in FIG. 1;

FIG. 5 is a top view of the protective and warming bonnet for food shown in FIG. 1;

FIG. 6 is a bottom view of the protective and warming bonnet for food shown in FIG. 1; and,

FIG. 7 is a front elevational view of the protective and warming for food shown in FIG. 1.
